UNITED STATES PATENT OFFICE

GEORGE S. NELSON, OF SALT LAKE CITY, UTAH

METAL FORM AND FORM HOLDER FOR CONCRETE JOIST AND SLAB CONSTRUCTION

Application filed July 19, 1929. Serial No. 379,447.

The present invention relates to improvements in metal forms and form-holders for use in concrete joist and slab construction and has for a general object the provision of forms requiring a minimum of false work and wood-forming for support.

One of the difficulties encountered in the use of metal forms previously used has been the provision of means to support the forms in upright position and to support the sides of the form where the sides are flexible. Various constructions have previously been proposed but these have largely been objectionable because of the amount of time and labor required for setting up and removing the forms due to their complex construction in some instances and due to the method of attachment to the falsework in other cases.

A general object of the present invention is the provision of forms and form-holders by means of which the forms may be firmly secured in proper position and which may be readily assembled and taken apart with a minimum of effort.

A further object of the invention is the provision of forms and form-holders which may be readily stacked for purposes of storage and shipment.

Still another object of the invention is the provision of forms and form-holders of such construction that accurate placing is made certain even when manipulated by an unskilled laborer so that the molding of joists of varying depths is precluded.

These and other objects of the invention will become more readily apparent upon a study of the following specification when read in connection with the accompanying drawings and appended claims.

In the drawings, Fig. 1 is a cross-sectional view of a construction showing two of my forms in place, the form holder of one being in closed position and that of the other being in open position.

Fig. 2 is a sectional view showing the method of forming bridging.

Fig. 3 is a sectional view illustrating the method of forming drop ends.

Fig. 4 is a side elevation of a single line

of forms showing the relative positions of the forms when in place.

Fig. 5 is an end view of what I call the "rider-form".

Fig. 6 is a side elevation of what I call 55 the "saddle-form".

Fig. 7 is an end view of the saddle-form.

Fig. 8 is a side elevation of the rider-form.

Fig. 9 is a front elevation of an end dia- 60 phragm which may be used in connection with the saddle-form.

Fig. 10 is a side elevation of the end dia- phragm shown in Fig. 9.

Fig. 11 is a plan view of the form holder 65 with the wedge removed.

Fig. 12 is a side elevation of the form holder with the wedge in place.

Fig. 13 is an enlarged sectional view of the wedge and link connection between the 70 arms of the form holder when the form holder is in closed contracted position.

Fig. 14 is an enlarged sectional view of the wedge and link connection between the 75 arms of the form holder when the form holder is in closed expanded position.

Fig. 15 is a cross-section through the line 1—1 of Fig. 14 with the wedge removed.

The rider form 2 is preferably made of a single sheet of metal bent into any desir- 80 able shape such as that illustrated in Figs. 5 and 8. Each side 4 of the rider form is provided with a plurality of vertically spaced slots or openings 6. The sides 4 are

sprung outwardly so that in normal unrestrained condition their position will be that indicated by the dotted lines 8 in Fig. 5. The saddle form 10 is also preferably made of a single sheet of metal but may be built up of a plurality of pieces if desired. Each 90

of the sides 12 of the saddle form is preferably provided with two sets of vertically spaced slots 14 as shown, the sets on either side being disposed oppositely from those on the other side. At one end of the saddle 95

form, the sides are provided with inwardly turned flanges 16 which extend from substantially the bottom of the sides to within a spaced distance 18 from the top 20 of the saddle form. An end diaphragm 22 is pro- 100

vided for the purpose of closing off the flanged end of the saddle form. The end diaphragm consists simply of a metal plate having one end bent as shown at 24 in Fig. 10, leaving a face portion 25 and a bent portion 27.

The form holder 26 which is illustrated in Figs. 11 to 15 will for convenience first be described per se and its relation to the forms discussed, subsequently. The form holder consists of two arms 28 which are preferably made of flat strips of metal. One end of each of the arms is bent slightly more than ninety degrees as at 30 leaving bent portions 32. The extremities of the bent portions are turned about opposite sides of a rectangular shaped link 34 at 36. Each of the arms is provided with a slot 38 at a spaced distance from its outer extremity, leaving portions 40 between the slots and outer extremities. Adapted to be inserted between the bent portions 32 of the arms is a wedge 42 which is held against upward movement by means of teeth 44, punched into the bent portions 32. The wedge 42 may be provided with a projection 43 to prevent its complete removal from the link 34 if desired. The use of the wedge allows for adjustability of the distance between the two arms of the form holder. Fig. 13 shows the wedge in position to allow the two arms to come closely together, whereas Fig. 14 shows the wedge positioned to hold the arms further apart.

In the actual process of forming a concrete slab and joist floor the false-work consisting of the soffits 46 and 48 is first set in place and supported at intervals by the necessary beams and posts. The false work is of course of rough construction but the soffits are positioned at spaced intervals conforming as nearly as possible to the width of the saddle and rider forms to be used.

After the false work has been completed the forms are mounted on the soffits by means of the form holders as illustrated in Figs. 1 to 4. In mounting the forms, the portions 40 of the arms of the form holder are inserted through oppositely disposed slots in the sides of the form desired to be mounted until each of the slots 38 is in alignment with its particular side of the form. The entire form holder is then displaced laterally until the ends of the slots 38 engage the ends of the slots 6 or 14 in the sides of the form thus locking the sides against longitudinal movement with respect to the arms. At this stage the steel forms are placed on the soffit forms with their bottom edges resting on the false work. By pulling down on the form holder, the sides of the form will be drawn together and will drop along the inner sides of the soffits upon which the form is being mounted.

The projecting portions 40 of the arms 28

will engage the tops of the soffits, however, and support the form. The form is now in place and the form holder is in open position. An illustration of this is shown in the right hand side of Fig. 1.

In order to lock the form into proper place it is now only necessary to insert the wedge 42 the proper depth and then to push the center of the form holder upward into closed position. Due to possible variations in the spacing of the soffits, one or two trials may be required before the wedge is inserted at just the proper depth but in any case a tight fit is insured. When the form holder is pushed upwardly the sides of the form will be pushed outwardly so that their lower edges will press tightly against the inner sides of the soffits, thus preventing the flow of material between the two and the portions 40 of the arms 28 will be brought to rest horizontally on the tops of the soffits thereby providing a secure support as shown in the left hand side of Fig. 1. In the course of this operation, the bent portions 32 of the arms 28 will be slightly sprung but this spring action will hold the form holder in closed position until its removal is desired. The teeth 44 also act to prevent the wedge from slipping, thereby assisting in holding the holder in closed position. Where additional security is desired against any danger of the form holder falling out of closed position, one or two strands of wire may be wound about the portions 32 near the bends 30.

The removal of the form is accomplished by simply pulling downward on the tool holder. In this operation the portions 40 of the respective arms 28 of the holder are drawn together sufficiently to allow downward passage between the soffit forms. Due to the notches 38 the sides of the form are consequently also drawn together so that the entire form is free to drop down between the soffit forms and is ready for use elsewhere. The removal of the forms does not disturb the false work which may be allowed to remain until the concrete has sufficiently set.

Due to the provision of the vertically spaced sets of slots in the sides of the forms, the forms may be held any desired distance above the soffit forms so as to mold a joist of proper depth. The utility of this is evident from the showing in Fig. 3, for example, where steel forms of the same height are used in the forming of drop ends by simply inserting the form holder of the lower form into higher slots than those engaged by the form holder of the higher form.

The saddle forms only may be used for forming ends and bridging as shown in Fig. 2. For all other purposes the rider form can be used but in actual construction work it has been found most advantageous to use

the saddle and rider forms alternately. In a practical building operation saddle forms are placed on the soffits at spaced intervals with their form holders in open position. The spaces between the saddle forms are then covered by resting rider forms over the ends of the saddle forms as shown in Fig. 4 after which the form holders of the saddle forms are moved into closed position. Thus in ordinary cases it will not be necessary to apply form holders to the rider forms but this may be done if required in order to effect proper rigidity when there is a heavy load, for example. In general practice but one form holder for the rider forms provides sufficient rigidity and support and I therefore provide these forms with but one set of substantially centrally located slots although as many sets of slots and as many form holders may be used for each form as desired. The saddle forms should preferably be provided with two sets of slots and two form holders.

When it is desired to use the saddle form for forming ends and bridging as shown in Figs. 2 and 3 it is only necessary to apply an end diaphragm to the flanged end. This is accomplished by simply inserting the bent portion 27 of the diaphragm into the spaces 18 between the top of the form and the upper ends of the flange 16, allowing the face portion 25 to extend downwardly and cover the end of the form. No nuts, bolts or other connections are required. When the concrete is poured its weight will bear against the face of the end diaphragm pressing it tightly against the outer flat surfaces of the flanges 16 so that a tight fit is insured and no concrete will leak through the form.

Having thus described my invention what I now claim as new and desire to secure by Letters Patent of the United States is as follows:

1. A metal form for use in concrete construction in which false work is used having a top, and flexible sides provided with oppositely disposed openings therein, a form holder comprising two spaced arms pivotally connected to a central link, said form holder projecting through two of said oppositely disposed openings in the sides of the form at each end, means for locking the sides of the metal form against longitudinal movement with respect to the arms of the form holder at the point of passage of the arms through the sides at the openings therein, and means for varying the space between the two arms, the said portions of the arms projecting through the openings in the sides being adapted to support the form from the false work.

2. A metal form for use in concrete joist and slab construction in which false work is used having a top, and sides provided with

oppositely disposed openings therein, inwardly turned flanges projecting from the sides at one end of the form, an end diaphragm covering the aforesaid flanged end of the form, a form holder comprising two spaced arms pivotally connected to a central link, said form holder projecting through two of said oppositely disposed openings in the sides of the form, means for locking the sides of the form against movement longitudinal of the arms of the form holder, and means for varying the space between the two arms and for preventing relative angular movement between the two, the portions of the arms projecting through the openings in the sides being adapted to support the form from the false work.

3. A metal form for use in concrete joist and slab construction having a top and sides, inwardly turned flanges projecting from the sides at one end of the form and extending from substantially the bottom of the sides to within a spaced distance from the top, an end diaphragm comprising a main flat portion and a bent portion at one end, said bent portion of the diaphragm being adapted to be inserted at one end of the metal form in the space between the aforesaid flanges and the top of the form, the main flat portion being adapted to cover the flanged end, and means for supporting the form and for holding the sides in extended position.

4. A metal form for concrete construction having a top and sides provided with oppositely disposed openings, a form holder comprising two arms connected to a rectangular link, each of said arms projecting through one of the aforesaid openings, means for locking the sides against movement longitudinally of the arms, and a wedge between said arms at the link connection for locking said arms against relative angular movement and for adjusting the length of the form holder.

5. A form holder for metal forms used in concrete construction, comprising two arms each having an end bent slightly more than ninety degrees, a rectangular link connecting said arms at the extremities of their bent portions, and a wedge adapted to be inserted between said bent portions and through said link, each of said arms having notches in their sides at spaced distances from their free ends.

6. A metal form for concrete construction having a top and sides provided with oppositely disposed vertically spaced openings, said sides having inwardly turned flanges extending to within a spaced distance from the top of the form at one end of said form, and an end diaphragm for covering the flanged end of said form, said end diaphragm having an upper bent por-

tion adapted to be inserted in the space between the inwardly turned flanges and the top of the form.

7. A metal form for concrete construction having a top and depending sides substantially at right angles thereto, said sides having inwardly turned flanges terminating at a spaced distance from the top, and an end diaphragm comprising a main flat portion 10 having a bent edge portion, said bent edge portion resting on the upper extremities of the side flanges whereby the main flat portion covers the space between the two flanged sides.
- 15 8. A metal form for use in concrete construction in which false work is used having a top and sides, and a detachable form holder comprising two pivotally connected arms having free ends engaging the sides 20 of the metal form to hold them firmly against the false work, means for locking said arms in their relative angular positions when holding the metal form firmly against the false work, and means for varying the 25 relative longitudinal positions of said arms thereby to vary the distance between the ends thereof engaging the sides of the metal form when said arms are in their aforementioned relative angular positions.
- 30 In testimony whereof I have hereunto set my signature.
